(57) **CLAIM**

The ornamental design for a stewpot, as shown and described.

DESCRIPTION

FIG. 1 is an upper right front perspective view of a stewpot, showing my new design;

FIG. 2 is a front view thereof;

FIG. 3 is a right side view thereof;

FIG. 4 is a top view thereof; and,

FIG. 5 is a bottom view thereof.

A rear view of the stewpot is omitted as it is symmetric in appearance to the front view of FIG. 2. A left side view of the stewpot is omitted as it is symmetric in appearance to the right side view of FIG. 3.

1 Claim, 5 Drawing Sheets
